UNITED STATES PATENT OFFICE

HERBERT S. JANDUS AND CHARLES E. RASMUSSEN, OF DETROIT, MICHIGAN, ASSIGNORS,
BY MESNE ASSIGNMENTS, TO GENERAL SPRING BUMPER CORPORATION, A COR-
PORATION OF MICHIGAN

DESIGN FOR A VEHICLE BUMPER

Application filed May 19, 1927. Serial No. 22,052. Term of patent 14 years.

To all whom it may concern:

Be it known that we, HERBERT S. JANDUS and CHARLES E. RASMUSSEN, citizens of the United States, residing at Detroit, in the county of Wayne and State of Michigan, have invented a new, original, and ornamental Design for a Vehicle Bumper, of which the following is a specification, reference being had to the accompanying drawing, forming part hereof, wherein

Fig. 1 represents a plan view and Fig. 2 a front elevation of a bumper exhibiting our new design.

We claim:

The ornamental design for a vehicle bumper, as shown.

HERBERT S. JANDUS.
CHARLES E. RASMUSSEN.
